(57) **CLAIM**

I claim the ornamental design for a combined cylinder and cylinder head for a motorcycle, as shown and described.

DESCRIPTION

FIG. 1 is perspective view of a combined cylinder and cylinder head for a motorcycle showing my new design;

FIG. 2 is a front elevation thereof;

FIG. 3 is a rear elevation thereof;

FIG. 4 is a right side view thereof;

FIG. 5 is a left side view thereof;

FIG. 6 is a top view thereof; and,

FIG. 7 is a bottom view thereof.

Portions of the drawings shown in broken lines form no part of the claimed design.
